CLAIM

The ornamental design for an ice scraper, as shown and described.

DESCRIPTION

FIG. 1 is a perspective view of an ice scraper showing our new design;

FIG. 2 is a front view thereof;

FIG. 3 is a left side view thereof, the right side view being a mirror image and symmetrical thereto;

FIG. 4 is a back view thereof;

FIG. 5 is a bottom end view thereof; and,

FIG. 6 is a top view thereof.
